GAME APPARATUS

Claude R. Kirk, Oak Park, and Edward E. Collison, Chicago, Ill., assignors to Standard Ticket Games Corporation, Chicago, Ill., a corporation of Illinois

Application November 30, 1934, Serial No. 755,267

5 Claims. (Cl. 273—121)

This invention relates to a game apparatus. It is an object of this invention to provide an improved game apparatus which is relatively simple and inexpensive in construction and efficient in use.

This application is related to our Patent No. 1,973,815 dated September 18, 1934, on a Game apparatus, and relates to and claims per se the anti-tilting device shown and described in our aforesaid patent and by means of which the score registering dial embodied in the game apparatus of our aforesaid patent is rendered invisible to the player, so that he can not see the score he has made, and the score-recording device is rendered ineffective, if the player attempts to operate the apparatus fraudulently by tilting the same out of its normal and proper or horizontal operating position.

Other objects will appear hereinafter.

20. The invention consists in the novel combination and arrangement of parts to be hereinafter described and claimed.

The invention will be best understood by reference to the accompanying drawing, showing the preferred form of construction and in which:

Fig. 1 is a fragmentary top plan view of the game apparatus embodied in our aforesaid patent and showing particularly the anti-tilting device with which the present application is concerned;

30. Fig. 2 is a vertical sectional view on line 2—2 in Fig. 1;

Fig. 3 is a fragmentary top plan view of the cabinet embodied in the new apparatus;

35. Fig. 4 is a vertical sectional view on line 4—4 in Fig. 1; and

Fig. 5 is a fragmentary detail view.

The game apparatus shown and described in our aforesaid patent composes a cabinet 10 within which is arranged a score registering dial 11, the face of the latter being visible to the player through a sight opening 32 which is provided in the top of the cabinet; the said registering dial 11 being operated by mechanism shown in our aforesaid patent and part of which is illustrated in

45. Fig. 1.

Arranged in the cabinet 10 is a vertical supporting wall 12 and pivotally suspended from this wall 12 is a pendulum 13, and when the cabinet 10 and its enclosed game apparatus are in 50 proper playing position the upper end portion of the pendulum 13 is latchingly engaged with a latch member 14, the latch member 14 being mounted upon a horizontal shaft 15 which extends transversely across the cabinet 10 adjacent 55 the lower end wall 16 thereof.

Pivottally connected to the latch member 14, as at 17, is a slide bar 18 which is slidably mounted on the vertical supporting wall 12 by means of a pin and slot connection 19. This slide bar 18 has a lateral extension 20 (Fig. 2) which projects over the peripheral surface of the score registering dial 11.

Carried by the shaft 15, adjacent a vertical supporting wall 21 which is arranged in the cabinet 10, is an arm 22 and pivotally connected to the arm 22 is a link 23, while pivotally connected to the link 23 at the lower end of the latter is a member 24 which floats upon, that is, is loosely mounted upon, a horizontal shaft 25 which carries the score recording or printing drum 26. This member 24 has a counter-weighted portion 27 which is normally latched in raised, or full line, position (Fig. 4) by latching engagement of the upper end portion of the pendulum 13 with the latch member 14.

If the player attempts to operate the game apparatus in the cabinet 10 fraudulently, by tilting the same and the cabinet 10 from their proper playing position, the upper end portion of the pendulum 13 is moved by gravity out of latching engagement with the latch member 14, whereupon the counterweighted portion 27 of the member 24 drops or pivots by gravity (counterclockwise, Fig. 4) upon its supporting shaft 25, thereby elevating or pivoting the member 24 into a position (as in dotted lines, Fig. 4) between the peripheral or printing face of the printing drum 26 and the pivotal impression-transmitting or pressure member 28, thus preventing the player from printing the score of the game upon the ticket web 33 which is fed between the pressure member 28 and the printing drum 26 by means not shown but embodied in our aforesaid patent.

At the same time, this motion of the counterweighted member 24—27 acts through the link 23 and the arm 22 to rotate the shaft 15 (clockwise, Fig. 4, counterclockwise, Fig. 2), thereby sliding the bar 18 (right to left, Fig. 2), and thus projecting the angled or lateral extension 20 of the slide bar 18 across the peripheral surface of the score-indicating or registering dial 11; thereby rendering the player's score invisible to him through the sight opening 32 which is provided in the top wall of the cabinet 10.

In order to reset the anti-tilting device into its normal or ineffective position, that is, in order to retract the lateral extension 20 of the slide bar 18 out from under the sight opening 32 through which the score-indicating dial 11 is visible, and to remove the stop member 24 from

its effective position between the printing drum 26 and the pressure member 28, it is necessary for the player to insert a proper coin into the coin aperture of the coin slide 29 and push the same inwardly from coin-receiving toward coin-discharging position (from bottom to top, Fig. 1, right to left, Fig. 5). This movement of the coin slide 29, acting through a link connection 30, rocks the shaft 31 and a segmental gear 34 carried thereby (counterclockwise, Fig. 4) and during this movement of the segmental gear 34 its upper edge engages a laterally projecting pin 35 which is carried by the counterweighted portion 27 of the member 24, thereby pivoting the counterweighted member 24-27 (clockwise, Fig. 4). This movement of the counterweighted member 24-27 retracts the same (from dotted to full line position, Fig. 4) out of effective position between the pressure member 28 and the printing drum 26, so that the pressure member 28 may again urge the ticket web 33 against the printing drum 26.

Also at the same time this movement of the stop member 24 acts through the link 23 and arm 22 to rock the shaft 15 (counterclockwise, Fig. 4, clockwise, Fig. 2), thereby pivoting the latch member 14 (clockwise, Fig. 2) and thus moving the slide bar 18 (left to right, Fig. 2). This movement of the slide bar 18 retracts the lateral extension 20 thereof out from under the sight opening 32 in the cabinet and thus again exposes the score-indicating dial 11 to the player. At the same time, this movement of the slide bar 18 reengages the latch member 14 with the upper end portion of the pendulum 13 so as to latch the counterweighted end portion 27 of the stop member 24 in raised and ineffective position (as in full lines, Fig. 4).

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what we claim as new and desire to protect by Letters Patent is:

1. In a game apparatus, the combination of: a cabinet; a score-indicating or registering dial in said cabinet and normally visible from a point outside said cabinet; a coin slide having a coin receiving aperture; a member movable over the peripheral surface of said registering dial and adapted when in effective position to render the latter invisible from outside said cabinet; means automatically moving said member into effective position when and if said cabinet is tilted from its normal and proper operating position; and means coacting with said coin slide and necessitating the insertion of a coin of proper denomination into the said coin aperture of the same to reset the said member back into its initial or ineffective position.

2. In a game apparatus, the combination of: a cabinet having a sight opening formed therein; a score-indicating or registering dial in said cabinet and normally visible from outside said

cabinet through said sight opening; a member movable into and out of position between said sight opening and said dial and when in effective position rendering said dial invisible through said sight opening; means automatically moving said member into effective position between said sight opening and dial so as to render the said dial invisible through said sight opening when and if said cabinet is tilted from its normal and proper operating position; and means for resetting said member back into its initial or ineffective position so as to render said dial visible through said sight opening.

3. In a game apparatus, the combination of: a cabinet having a sight opening formed therein; a score-indicating or registering dial in said cabinet and normally visible from outside said cabinet through said sight opening; a member movable into and out of position between said sight opening and said dial and when in effective position rendering said dial invisible through said sight opening; means automatically moving said member into effective position between said sight opening and dial so as to render the said dial invisible through said sight opening when and if said cabinet is tilted from the normal and proper operating position; a coin slide having a coin-receiving aperture; and means coacting with said coin slide and necessitating the insertion of a coin of proper denomination into the coin-receiving aperture of the same to reset said member back into its initial or ineffective position so as to render said dial visible through said sight opening.

4. In a game apparatus, the combination of: a cabinet; a score-printing drum in said cabinet; a pressure or inscription-transmitting member for urging an inscription-receiving web against the peripheral or printing face of said printing drum; a member movable between said pressure member and the peripheral or printing face of said printing drum and when in effective position preventing said pressure member from urging the said inscription-receiving web against the peripheral or printing face of the said printing drum; means automatically moving said member into effective position when and if said cabinet is moved from its normal and proper operating position; and means for resetting said member back into its initial or ineffective position.

5. In a game apparatus, the combination of: a cabinet; a score-printing drum in said cabinet; a pressure or inscription-receiving web against the peripheral or printing face of said printing drum; a member movable between said pressure member and the peripheral or printing face of said printing drum and when in effective position preventing said pressure member from urging the said inscription-receiving web against the peripheral or printing face of the said printing drum; means automatically moving said member into effective position when and if said cabinet is moved from its normal and proper operating position; a coin slide having a coin-receiving aperture; and means coacting with said coin slide and requiring the insertion of a coin of proper denomination into the coin-receiving aperture of the same to reset said member back into its initial or ineffective position.
